UNITED STATES PATENT OFFICE.

ADAM EDELMANN, OF GERMANTOWN, NEW YORK.

VEHICLE-SPRING.

SPECIFICATION forming part of Letters Patent No. 340,036, dated April 13, 1886.

Application filed January 14, 1886. Serial No. 188,612. (No model.)

To all whom it may concern:

Be it known that I, ADAM EDELMANN, of Germantown, county of Columbia, and State of New York, have invented a new and Improved Spring for Lumber-Wagons and other Vehicles, of which the following is a full, clear, and exact description.

The object of my invention is to provide a new and improved spring for lumber-wagons and other vehicles, which spring has a free and easy movement with a light or a heavy load, and which can be placed on the vehicle or removed from the same at pleasure in a very few moments.

15 The invention consists of a spring composed of two convex members, which are centrally united at their respective backs.

The invention also consists in the construction and arrangement of parts, as will be hereinafter fully described and claimed.

Reference is to be had to the accompanying drawings, forming a part of this specification, in which similar letters of reference indicate corresponding parts in all the figures.

25 Figure 1 is a side elevation of my improved spring for lumber-wagons and other vehicles. Fig. 2 is a plan view of the same, parts being broken out. Fig. 3 is a perspective view of a modification.

30 The spring A consists in two convex members, B and C, which are centrally united at their backs by means of bolts D or other suitable devices. Each member B and C may be provided with one, two, or more plates, B' and C'.

35 The ends of the upper member, B, of the spring A are provided with recesses E, and the lower member, C, is provided at each end with two downwardly-extending lugs, F. The 40 spring A is placed on the bolster G in such a manner that the outer ends of the member C ride on the upper edge of the bolster G, being held in place on the bolster by the lugs F, which extend on each side of the bolster.

The recesses E of the upper member, B, fit 45 over the stakes H of the bolster, and thereby prevent a sidewise movement of the spring, but allow a lengthwise expansion. The recesses E of the upper member and the lugs F of the lower member hold the spring A securely in place on the bolster G.

The upper member, B, of the spring A may be square at its end, not having the recesses E, and be provided with a malleable-iron shoe, I, riveted or otherwise secured to the 55 ends of the member B, and having a recess, I', similar to the recess E. This shoe can be adjusted at the ends of the member B to suit wagons having their stakes H a greater or less distance apart.

It will be seen that as the spring is not permanently fastened to the bolster it can be removed from the same very easily and rapidly.

The ends of the lower member, C, of the spring A may be clipped lengthwise to the 65 axles of the wagon, and the upper member attached at the outer ends to the under side of the wagon-box.

Having thus fully described my invention, I claim as new and desire to secure by Letters 70 Patent—

1. A spring composed of two members centrally united at their backs, of which the lower member is provided at its ends with downwardly-extending lugs and the upper member 75 is provided with recesses, substantially as herein shown and described.

2. The spring A, composed of the member B, having recesses E, and of the member C, having lugs F, said members being fastened 80 together by means of the bolts D or other suitable devices, in combination with the bolster G, having the stakes H, substantially as herein shown and described.

ADAM EDELMANN.
